UNITED STATES PATENT OFFICE

ARTHUR M. BARRETT, OF WINNETKA, ILLINOIS, ASSIGNOR TO BARRETT-CRAVENS COMPANY, OF CHICAGO, ILLINOIS, A CORPORATION OF ILLINOIS

LIFT TRUCK

Application filed July 21, 1927. Serial No. 207,451.

My invention relates to lift trucks of the type comprising a main frame supported on wheels and arranged to be steered by means of a steering handle which also serves 5 as a lifting lever to raise a lifting frame mounted on the main frame to move vertically with respect thereto to raise and lower the load carried by such lifting frame. When the lifting frame is in its lowered position the truck is adapted to be backed under a platform on which the load is placed, and then by operating the steering handle the lifting frame is raised to lift the platform with its load so that it can be transported and deposited in some other place. 15 My present invention has to do with improved means for raising the lifting frame and for controlling its descent, and with improved means for mounting the lifting frame 20 on the main frame.

Lift trucks of this description are employed to lift loads that differ widely in weight, and, therefore, it is desirable that the lifting mechanism be so designed that 25 when lifting a light load, which requires comparatively slight expenditure of power, the operation may be performed quickly by a single sweep of the lifting lever, whereas, when lifting a heavy load, the operation may 30 be performed by repeated short strokes of the lifting lever while it is in a position to be operated to the best advantage, thereby making the lifting operation easier. Also, it is desirable to provide means for holding 35 the load securely against descent at all stages of the lifting operation, especially where it is lifted by repeated strokes of the lifting lever. These objects are accomplished by my improved construction, as will more clearly appear from the detailed description 40 thereof that will presently be given.

With regard to the mounting of the lifting frame upon the main frame, it has heretofore been the practice to mount the rear 45 wheels on an axle journaled in the side bars of the main frame, and to support the rear portion of the lifting frame upon such axle by means of swinging links, the arrangement being such that the axle turns in its 50 bearings when said links are swung fore and

aft by endwise movement of the lifting frame to raise or lower said frame. This manner of mounting the rear axle and the rear portion of the lifting frame has been found to be objectionable because the bearings of the axle in the frame after a time become worn, so that, because of the loose joints and lost motion that result, the truck does not operate smoothly and steadily, and consequently the full lift is not attained. My improved construction avoids this objection also, as will presently appear.

In the accompanying drawings I have illustrated a lift truck in which my improvements are embodied in the form that I consider preferable, and I shall now proceed to describe specifically the truck illustrated, but it is to be understood that the generic features of my invention may be embodied in various other forms, as will be manifest to those skilled in the art, and, therefore, I do not wish the claims hereinafter made to be limited to the specific construction shown and described, except in so far as they may be directed to particular features of such construction.

Referring to the drawings,—

Fig. 1 is a plan view of my improved truck, part of the lifting lever or steering handle and its connections being shown in horizontal section;

Fig. 2 is a view partly in side elevation and partly in longitudinal vertical section, showing the arrangement of the lifting devices and the means for holding the lifting frame against descent;

Fig. 3 is a vertical cross-section of the front portion of the truck on line 3—3 of Fig. 1, showing the front or steering wheels and their connections, one of said wheels being in elevation;

Fig. 4 is a section on line 4—4 of Fig. 2, showing the manner of mounting the rear portion of the truck and the rear axle and wheels;

Fig. 5 is a similar view showing a slightly modified arrangement;

Fig. 6 is an enlarged partial longitudinal vertical section on line 6—6 of Fig. 1;

Fig. 7 is an approximately horizontal sec-

tion on line 7—7 of Fig. 2, illustrating more in detail the means for holding the lifting frame against descent;

Fig. 8 is a cross-section on line 8—8 of Fig. 6;

Fig. 9 is a cross-section on line 9—9 of Fig. 6, illustrating parts of the lifting mechanism;

Fig. 10 is a longitudinal vertical section on line 10—10 of Fig. 1, showing part of the lifting mechanism and the pedal by which the descent of the lifting frame is effected;

Fig. 11 is a section on line 11—11 of Fig. 2, showing part of the lifting mechanism;

Fig. 12 is a cross-section on line 12—12 of Fig. 11;

Fig. 13 is a perspective view of one of the bearing frames;

Fig. 14 is an enlarged longitudinal vertical section on line 14—14 of Fig. 1, showing the arrangement of two of such bearing frames; and

Fig. 15 is a similar section on line 6—6 of Fig. 1, the operating connections being omitted.

In the present instance I have shown my improvements embodied in a lift truck in which the wheel supported main frame 13 comprises two side bars 14, 15, the forward end portions of which are parallel for a short distance, as shown at *a* in Fig. 1, while the intermediate portions of said side bars converge rearwardly, as shown at *b*, the rear end portions *c* of said bars being also parallel and somewhat closer together than their front end portions. The parallel front portions of said bars are firmly held in fixed relation to each other by securing them to the opposite ends of a transverse cross-head 16, as best shown in Fig. 3, the end portions 17, 18 of which extend downward to the points of their connection with the side bars 14, 15. In the illustrated construction these parts are connected together by bolts 19, as best shown in Fig. 1. The cross-head 16 is provided with a central downwardly projecting tubular boss 20 which forms a bearing for a vertically disposed king bolt 21 that is connected with the steering wheel or wheels. In the present instance two steering wheels 22 are provided, mounted upon the opposite end portions of a transverse front axle 23 that extends through a hole in the lower portion of the king bolt 21 and through a horizontally disposed spacing sleeve 24 mounted on said axle between the wheels. This sleeve is provided with a hole that is aligned with the bore of the boss 20, and the lower end of the king bolt 21 fits in said opening, thereby holding the sleeve 24 in place. A set screw 25, screwed in the lower end of the king bolt 21 so that it binds against the axle 23, holds the axle in place. Between the lower end of the boss 20 and the upper surface of the sleeve 24 I provide an

anti-friction bearing to reduce friction between these two members and make steering easier. In the illustrated construction this anti-friction bearing comprises an inner annular raceway 26 supported by the sleeve 24, an outer annular raceway 27 fitted in a pocket in the lower end of the boss 20, and tapered rollers 28 interposed between said raceways, to sustain the downward thrust of the load. These bearings may if desired be made adjustable in any suitable way. Since the mounting of roller bearings of this kind so that they may be adjusted is not new, it is deemed unnecessary to illustrate means for that purpose.

It will be apparent from the foregoing description that the front portion of the main frame, and the load imposed thereon, is movably sustained by the front wheels through the boss 20, the sleeve 24 and the axle 23, and that the wheels may be turned to steer the truck by rotating the king bolt 21 about a vertical axis. For steering purposes the king bolt 21 is provided with a steering head 29 mounted thereon above and bearing upon the upper surface of the cross-head 16, said steering head being non-rotatably secured to the king bolt in any suitable way, as by a pin 30. A steering handle 31, which also serves as a lifting lever, is pivotally connected at its lower end by a transverse bolt 32 with upwardly and forwardly projecting ears 33 carried by the steering head, so that said steering handle may swing up and down, and may also be used to rotate the steering head. In the illustrated construction the steering handle 31 comprises two bars 34 spaced apart at their lower ends and arranged to lie adjacent to the outer faces of the ears 33, with which, as above stated, they are pivotally connected by the bolt or pin 32. The outer ends of the bars 34 are connected together in any suitable way, and are provided with the usual cross-bar (not shown) by which the operator swings said handle to raise the load and to steer the truck. Also pivoted upon the bolt 32 and located between the ears 33 is a shackle member in the form of a horn 35 that extends rearwardly and upwardly from the pivot 32, back of the handle 31, its upper end being adapted to swing toward and from the handle and to be connected therewith by a latch 36 carried by the handle, as best shown in Fig. 2. This latch is pivoted on the handle between the side bars by means of a pivot 37 so that it rocks about a horizontal axis. At its rear end it is provided with a hook 38 adapted to engage a hook 39 at the upper end of the horn 35, and at its forward end it is provided with an arm 40 that extends across one or both of the bars 34 of the steering handle and serves to limit the downward movement of the rear end of the latch. The latch is also provided with a counterbalance weight 41 that is adapted to

hold it either in a downwardly and rearwardly inclined position, as shown in Fig. 2, or in an upwardly and rearwardly inclined position at approximately ninety degrees from the position shown in said figure, and with a depending arm 41^a that is adapted to strike the horn 35 when the steering handle is moved rearwardly, to positively move the hook 38 into position to engage the hook 39. The horn 35 is provided near its lower end, and at a point back of the pivot 32, with a transverse lug or stop 42 that is adapted to engage the upper surface of the steering head 29 when the horn is in an approximately vertical position, to keep the horn from swinging back further, while permitting it to swing forward when it is actuated by the steering handle during the operation of lifting the load. It will be apparent from Fig. 2 that by swinging the steering handle rearwardly from the position there shown the latch 36 will automatically engage over the upper end of the horn 35, thereby operatively connecting the steering handle with said horn. If, then, the steering handle be swung forward and downward the horn 35 will swing with it, both parts turning about the pivot 32. The horn 35 will also swing laterally about the vertical axis of the steering head when the handle is operated to steer the truck. The horn 35 serves to transmit power applied to the steering handle, to the lifting mechanism by which the lifting frame is raised, as will be presently described.

The rear ends of the side bars 14, 15 of the main frame are supported upon and secured to a non-rotating rear axle 43, as best shown in Figs. 1 and 4, which axle extends through holes in, and is pinned to the rear end portions of said side bars, and carries the rear wheels 44 of the truck. These wheels are not mounted directly upon the axle 43, as is the usual practice, but are mounted upon sleeves 45 journaled on the opposite end portions of said axle between the rear ends of the side bars 14, 15 and cotter pins 46 that extend through the end portions of the axle. Thus said sleeves are held against endwise movement on the axle. In the present instance anti-friction devices, preferably rollers 47, are provided between the sleeves 45 and the hub portions of the wheels 44. The rear end portions of the side bars 14, 15 are secured together and spaced apart by a transverse angle bar 48, best shown in Fig. 1, said bar being preferably U-shaped and having its turned ends secured to said side bars by rivets 49. This transverse bar also serves to support certain other parts of the mechanism, as will be hereinafter explained.

The lifting frame is rectangular in form and is best made of a bar bent to U-shape to provide parallel side members 50, 51, and a transverse rear end member 52. The side members 50, 51 are connected near their front ends by a transverse U-shaped plate 53, the downturned ends of which are firmly secured to the side members 50, 51 in any suitable way, as by bolts 54 shown in Fig. 9. The forward edge of the plate 53 is provided with an upturned lip 55, best shown in Fig. 10, which limits the extent to which the truck may be shoved under a load carrying platform. The rear end portions of the side bars 50, 51 are connected and braced by a transverse angle bar 56, as best shown in Figs. 1 and 2, which bar serves also as a bearing member for the lifting connections at the rear end of the truck.

The lifting frame is supported on the main frame for vertical movement with respect thereto by means of swinging links at the front and rear end portions of said frames. The front links, indicated by reference numerals 57, 58, are pivotally connected at their lower ends to the parallel front portions of the side bars 14, 15 by bolts 59, 60, as shown in Fig. 1, the upper ends of said links being connected with the front ends of the side members 50, 51 of the lifting frame by bolts 61, 62, respectively. The links that support the rear portion of the lifting frame are indicated by the numerals 63, 64, the lower ends of which links are mounted on the end portions of the sleeves 45, which, as has been explained, are mounted on the end portions of the rear axle 43. The upper ends of the links 63, 64 are journaled on studs or reduced portions 65, 66 at the opposite ends of a cylindrical bearing member 67 that is adapted to bear in the inner angle of the angle bar 56, secured to the lifting frame, as best shown in Fig. 2, said bearing member being also supported upon the inner end portions of the sleeves 45 by arms 68, 69, best shown in Fig. 4. Preferably the parts 67, 68, 69 are in the form of a unitary casting.

It will be noted that by this construction the rear portion of the lifting frame is supported on the rear axle through the sleeves 45, by two supporting members at each side of the truck, the supporting members of each pair being located at opposite sides of the corresponding wheel 44, so that the rear portion of the lifting frame is very stably supported. The several links supporting the lifting frame are arranged to occupy an upwardly and rearwardly inclined position when the lifting frame is in its down or load receiving position, so that by drawing the lifting frame forward with reference to the main frame said links will swing in a clockwise direction as viewed in Fig. 2 to raise the lifting frame to lift the load for transport. By mounting the swinging supports at the rear of the lifting frame on the sleeves 45 instead of on a rotatable axle journaled in the side members of the main frame, as is the usual practice, the truck is made much more durable, and it operates more smoothly,

since the bearing surfaces between the sleeves 45 and the shaft 43 are much more extensive, so that wear is negligible and the life and value of the truck are greatly increased.

Fig. 4 illustrates the several connections with the rear axle where the main frame is designed as shown in Fig. 1, with its side members converging toward the rear, but as shown in Fig. 5, the same mounting arrangement for the rear portion of the lifting frame may be employed where the side members of the rear frame are parallel and underlie the side members of the lifting frame in accordance with the customary practice. 10 In the latter figure one of the side members of the lifting frame is indicated by the reference numeral 15^a, the other, which is not shown, being similarly arranged. These side members, instead of connecting with the rear axle 43 between the supports 68, 69, are connected with the end portions of said axle outside of the links 63, 64. In this construction also the axle 43 does not turn in the side bars of the main frame, but the sleeves 45 turn on said axle; consequently there is 20 no wear between the axle and such side bars.

The lifting mechanism for raising the lifting frame, as has been remarked, is operated by the steering handle 31, which constitutes 30 also a lifting lever, and it comprises means for moving the lifting frame endwise to accomplish its lifting movement through the action of the swinging links that support it on the main frame. Such lifting mechanism is best shown in Figs. 1, 2 and 6, and it includes an operating rod that is adapted to be reciprocated by swinging the lifting lever up and down, and connections by which the lifting frame is raised by movement of said 35 operating rod in one direction only, in the present instance in a forward and upward direction, so that the load may be raised by a step by step operation. Provision is also made by which the leverage of the lifting lever on the lifting mechanism may be varied to suit different conditions, as where the load is a heavy one it is desirable to increase such leverage, whereas with a light load greater speed may be obtained by reducing such 40 leverage. Referring now more particularly to Fig. 6, it will be seen that the lifting mechanism comprises an upwardly extending arm 70 mounted at its lower end upon pivots 71 journaled in lugs 72 that project rearwardly 45 from the central portion of the cross-head 16, so that said arm is adapted to swing fore and aft about a horizontal axis. Said arm is preferably slightly arcuate in form, and is provided in its rear margin with a series of 50 notches 73 at different distances from the pivots 71, which notches are adapted to receive the rear end of a link 74 which is looped over the horn 35, thereby connecting said arm with said horn in such manner that by 55 swinging the lifting lever 31 about its pivot

32 the arm 70 may be rocked about its pivot. To provide for moving the arm 70 rearwardly as well as forwardly by the operation of the lifting lever 31 and to prevent accidental disengagement of the link 74 from said arm, 70 said link is provided with a horizontally swinging latch 75 pivotally supported by a cross-bar 76 carried by said link, said latch being arranged to swing into or out of position to hold the link 74 in engagement with one of the notches 73. As clearly shown in Fig. 6, the latch 75 has a downwardly extending arm 77 at its forward end which turns in a bearing in the bar 76, so that the latch 75 may be swung over into alignment with the arm 70, and thereby prevent endwise movement of the link with respect to said arm. By swinging the latch 75 laterally away from the arm 70 the link may be moved out of its notch 73 to shift it up or down into position to engage one of the other notches, thereby varying its distance from the pivots 71 and consequently varying the leverage of the lifting lever 31 on said arm. A spring 78, located between a pin 79 on the lower end of the arm 77 and the under surface of the cross-bar 76, holds the horizontal portion of the latch 75 in frictional engagement with the upper surface of the bar 76 and thereby holds it in the different positions to which it may be adjusted. The bar 76 lies immediately back of the lower portion of the horn 35, and the upper end of the horn 35 is adapted to be engaged by a transverse pin 80 carried by the lifting lever 31, to transmit rearward movement of said lifting lever to said horn; thus by reason of the engagement of the horn with the cross bar 76 it transmits such rearward movement to the arm 70. It will be apparent, therefore, 105 that when the parts are in the position shown in Fig. 6 forward and backward movement of the lifting lever 31 will rock the arm 70 about its pivots 71. If it be desired to operate the lifting lever independently of the horn 35 and of the arm 70 said horn may be disengaged from said lever by moving the latch 75 out of operative position, whereupon said lifting lever may be used purely as a steering handle without operating the lifting mechanism. As shown in Fig. 12, the arm 70 is best made somewhat cylindrical in cross-section, so that the link connection 74 between the lifting lever and said arm may turn laterally in the notches 73, to permit the lifting lever to be swung laterally in steering the truck without disengaging it from the lifting mechanism. The lifting lever may therefore be operated through a wide range of steering 110 positions to lift the lifting frame.

Power is transmitted from the arm 70 to the lifting frame, to lift it by drawing it forward, through an operating rod 81 pivotally connected at its forward end with the lower portion of the arm 70 by a pivot 82 located

adjacent to the pivot 71 of said arm. The rod 81 extends downward and rearward, and for the greater part of its length is screw-threaded, as shown at 81^a in Figs. 6 and 11, the screw-threaded portion operating through a nut 83 mounted concentrically in a ratchet wheel 84 and secured thereto so as to rotate therewith. Said nut is held against endwise movement in the ratchet wheel 84 in any suitable way, as by providing it with a circumferential bead 85 that fits in a groove in the hub portion of said ratchet wheel, as best shown in Figs. 6 and 11. The ratchet wheel 84 and nut 83 are mounted in an opening 86 in a transversely disposed frame 87 provided at its forward side with a central globular breast or bearing surface 88 that bears against rounded seats in the rear surface of a vertical plate or flange 89 that depends from the forward portion of a bearing frame 90, best shown in Figs. 6 and 9, which bearing frame is firmly secured to the under side of the plate 53. The end portions of the frame 87 are rounded at the top, as shown at 88^a in Fig. 14, to provide spaced rocker bearing surfaces that bear against the under surface of the horizontal portion of the frame 90 at opposite sides of the breast portion 88, as best shown in Figs. 14 and 15. The breast 88 does not bear on the under surface of the frame 90, and the bearing surfaces 88^a do not bear on the flange 89. Thus I provide a three-point bearing between the bearing frame 87 and the lifting frame, the advantages of which will be explained later. The end portions of the frame 87 are connected with the frame 90 at the upper portion of the flange 89, by means of bolts 91 that extend through holes 92 in said flange and through tapered holes 93 in the frame 87. Springs 94 are mounted on the rear ends of said bolts between the heads 95 thereof and the end portions of the frame 87, to yieldingly hold said frame in bearing engagement with the flange 89 and the under surface of the frame 90. As best shown in Fig. 2, the bolts 91 are inclined at an angle such that they draw the bearing surfaces 88, 88^a upward as well as forward, so that the frame 87 has bearing contact with the under surface of the frame 90 as well as with the vertical surface of the flange 89, thereby assuring a proper bearing contact between said parts. The holes 93 are flared forwardly so as to allow a limited rocking movement of the frame 87.

The operating rod 81 passes through an opening 96 in the upper portion of the flange 89, and also through openings 97, 98 in the front and rear portions of the frame 87 in alignment with the bore of the nut 83, as best shown in Figs. 6 and 11, and these holes for the passage of the operating rod 81 are so disposed with reference to the position of the bolts 91 that said bolts extend upward and forward at a slightly greater angle than said

operating rod, so that they resist any tendency of said operating rod to move the bearing surfaces 88^a out of proper contact with the under surface of the frame 90.

Since the frame 90 is firmly secured to the plate 53, and said plate is fixedly secured to the lifting frame, it will be apparent that if the operating rod 81 be held against endwise movement with relation to the bearing frame 90, forward and upward pull on said operating rod will pull the lifting frame forward and upward, thereby raising the load carried by it. It is also evident that if the nut 83 and ratchet wheel 84 be left free to rotate, the operating rod 81 may be reciprocated through the nut and by such reciprocation, owing to the screw-threaded engagement between these parts, will rotate it and the ratchet wheel 84 in one direction or the other, depending on the direction in which said rod is moved. If, however, said nut be held against rotation, relative movement between it and the operating rod 81 will be prevented, and consequently if the operating rod 81 be then reciprocated the nut 83 will move with it, and such movement will be transmitted through the frames 87 and 90 to the lifting frame. To apply this construction for the purpose of lifting the lifting frame by a step by step movement it is, of course, necessary that the nut 83 be held against rotation when the operating rod 81 is drawn forward and upward to lift the lifting frame, and that it be permitted to rotate upon the operating rod 81 when said rod is moved backward and downward on its reverse stroke, so that the lifting frame may maintain the position to which it is raised on the forward stroke, under the control of suitable holding means that will be described later; and the ratchet wheel 84 is one of the instrumentalities provided to accomplish that end. Associated with said ratchet wheel is a detent lever 99, which, in the present instance, is pivotally connected with the frame 87 by a pivot 100, and is provided with a tooth 101 adapted to engage the teeth of the ratchet wheel 84, as shown in Fig. 9. Said lever extends transversely of the lifting frame and is adapted to swing vertically about its pivot, to carry the tooth 101 into or out of position to engage said ratchet wheel. It is also provided with an arm 102 that extends in one direction from the pivot 100 and is pressed downward by a spring 103, which tends to hold the detent in operative engagement with the ratchet wheel. The free end 104 of the detent lever 99 extends beyond the frame 90 and projects under a trip lever 105 that is pivotally mounted on a depending flange 106 that forms a part of the frame 90, by means of a pivot 106, as shown in Fig. 10. The lever 105 engages the arm 104 of the detent 99 at a point forward of the pivot 106 of said lever, so that downward movement of the lever 105 effects down-

ward movement of the detent lever, thereby carrying its tooth 101 out of engagement with the ratchet wheel 84. The forward end of the lever 105 extends up to a point adjacent to and somewhat back of the cross-head 16, as best shown in Figs. 1 and 10, where it is provided with a foot rest 107, so that it may be conveniently depressed by the operator when he desires to release the ratchet wheel 84. A spring 108 mounted on a vertically disposed bolt 109 is arranged to exert upward stress on the forward portion of the foot lever 105 to hold it in its normal position and leave the detent lever 99 free to engage the ratchet wheel 84 under the stress of the spring 108. As shown in Fig. 10, the bolt 109 passes through a suitable opening in the frame 90, and its lower end extends through a laterally projecting lug 110 carried by the lever 105, and is secured by a nut 111 screwed on said bolt below said lug. The spring 108 is interposed between the upper surface of the frame 90 and the head 112 of the bolt 109 so that it tends to move said bolt upward for the purpose stated.

The teeth of the ratchet wheel 84 and the tooth 101 on the detent lever 99 are so arranged that they cooperate to prevent rotation of the nut 83 in the direction in which it would be caused to rotate by forward and upward movement of the operating rod 81 through said nut, but permit rotation of said nut in the opposite direction. Consequently, when the operating rod 81 is pulled forward and upward by the operation of the lifting lever 31, it does not move with respect to the nut 83, but carries said nut and the ratchet wheel 84 along with it, which, of course, draws the lifting frame forward and upward. At the conclusion of each lifting stroke of the lever 31 it is swung back preparatory for the next stroke. During this latter operation the lifting frame is held in the position to which it has been lifted by the holding mechanism soon to be described, and the operating rod 81 moves backward and downward through the nut 83, which, by reason of its screw-threaded engagement with said rod, rotates in a clockwise direction as viewed in Fig. 9, tripping over the tooth 101. Manifestly, therefore, the lifting frame may be raised by a step by step operation, or, in cases where the load is comparatively light, by first moving the operating rod 81 backward and downward to a sufficient extent, the lifting frame may be raised high enough by a single stroke of the operating lever 31.

It is obviously necessary that means be provided for holding the lifting frame in its elevated position, and also at any intermediate elevation that marks the end of an operating stroke of the lifting lever, and it is desirable, also, that means be provided for checking the descent of the lifting frame, especially when it is loaded. For this purpose I employ

holding devices similar in some respects to the lifting devices above described. Such holding devices comprise a longitudinally movable rod 113, which is also rotatable, the rear portion of which rod is screw-threaded. As this rod performs the function of holding the lifting frame against descent it may conveniently termed a holding rod, although it also serves as a piston rod to check the descent of the lifting frame. The holding rod 113 extends longitudinally of the truck, and is preferably located midway between the opposite side members thereof. At its rear end it carries a piston 114 that operates in a cylinder 115, the rear end of which is supported by a cross-head 116 secured to the transverse bar 48, as best shown in Figs. 1 and 7. This cross-head is similar in general design to the bearing frame 87, and it has a central breast portion 121 that is seated against the front or vertical face of the bar 48, as shown in Fig. 7. It also has rounded end bearing surfaces that bear against the upper surface of the horizontal flange 48^a of said bar 48, as shown at 121^a in Fig. 2. The end bearing surfaces of this cross-head are, of course, at the under sides thereof instead of being at its upper sides as is the case with the end bearing surfaces 88^a of the frame 87. This difference in arrangement is due to the fact that the cross-head 116 applies the downward thrust of the load to the transverse bar 48, whereas in the case of the frame 87 the lifting stress is applied through the frame 87 in an upward direction to the lifting frame. As shown in Fig. 7, the cross-head 116 is connected with the transverse bar 48 by bolts 117 at opposite ends thereof, corresponding to the bolts 91, which bolts pass through flared openings 118 therein. Springs 119 mounted on said bolts between the heads 120 thereof and the end portions of the cross-head hold said cross-head with its three points of contact properly seated against the vertical and horizontal surfaces of the bar 48.

The forward end of the holding rod 113 is movable longitudinally through a stuffing box 122 at the forward end of the cylinder 115, and the screw-threaded portion of said rod operates through a nut 123 secured in said cylinder, preferably midway of the length thereof, as best shown in Figs. 6 and 7. Inasmuch as the position of the nut 123 is fixed, manifestly the holding rod 113 cannot be moved endwise except by rotating it to screw it through said nut, and therefore, if said rod be held against rotation, it will also be held by said nut against longitudinal movement.

The front end of the holding rod 113 extends through a bearing frame 124 similar in most respects to the bearing frame 87. This bearing frame 124 extends transversely of the truck and has a spherical or breast portion 125 at the front that bears against a

rounded seat in a depending flange 126 carried by the frame 90 and located back of the position occupied by the bearing frame 87, as best shown in Fig. 6. The frame 124 also has rounded end bearing surfaces 125^a at the top that bear against the under surface of the frame 90, which is extended back of the flange 126 for that purpose, as best shown in Figs. 13 and 14. Bolts 127, similar to the bolts 91, and similarly arranged, serve to hold the frame 124 in proper bearing engagement with the horizontal and vertical bearing surfaces on the frame 90, said bolts being inclined in the same manner as that described for the bolts 91, and for a like purpose. Springs 128 are provided on the bolts 127 and serve the same purpose as the springs 94. By this construction the bearing frame 124 has three points of contact with the frame 90, and may rock upon such bearing surfaces to accommodate itself to the movement of the lifting frame. By providing the check connections between the main and lifting frame, and the lifting connections between the lifting devices and the lifting frame, with the three points of contact, as described, exact and correct line-up of the holding devices, including the release check, and the lifting devices, is obtained regardless of any mal-adjustment or misalignment of the frames themselves, or of the mechanism at the front of the truck for operating the lifting devices.

It has been explained that the holding rod 113, because of its screw-threaded engagement with the stationary nut 123, must be rotated in order to move endwise with respect to the main frame. The front end of said rod is rotatably connected with the lifting frame, and is held against endwise movement with respect thereto, so that when the lifting frame is raised or lowered, because of its coincident endwise movement, it moves the holding rod endwise relatively to the main frame. Obviously, therefore, the lifting frame may be held at any elevation by holding the holding rod against rotation. The devices by which this is accomplished are best shown in Figs. 6, 7 and 8. Referring first to Fig. 7, it will be seen that the forward end of the holding rod 113 extends through the frame 124 and is secured thereto by nuts 129. The frame 124, like the frame 87, is provided with an opening or pocket 130 to receive a ratchet wheel 131 which is mounted upon and secured to the holding rod 113 so that it rotates therewith, said ratchet wheel being held against lateral movement by the side walls of the pocket 130. This also further secures the holding rod against endwise movement with relation to the lifting frame. The ratchet wheel 131 is normally held against rotation in one direction by a detent 132 mounted on a pivot 133 carried by the frame 124, said detent having a tooth 134 that is adapted to engage the teeth of said ratchet

wheel. The detent 132 is disposed transversely of the truck, and has a laterally projecting arm 135 that extends over the foot lever 105 at a point back of its pivot 106, as best shown in Fig. 10. By this construction, when the front end of the foot lever is depressed by the operator, its rear end rises and lifts the arm 135 of the detent 132, thereby moving its tooth 134 out of engagement with the ratchet wheel. As has been explained, the operation of this foot lever also operates the detent 99 to release the ratchet wheel 84 that forms a part of the lifting mechanism, so that by operating said lever both ratchets may be released. The arrangement of these parts is such that when the foot lever is operated the ratchet wheel 84 is first released and immediately thereafter the ratchet wheel 131 is released, the purpose of which arrangement is to avoid danger of accident by releasing the lifting mechanism before the holding mechanism is released. A spring 136, mounted between the frame 90 and the arm 135 of the detent 132, normally holds said detent in operative relation to the ratchet wheel 131, as best shown in Fig. 8.

From the foregoing description it should be clear that when the parts are in their normal position the engagement of the detent 132 with the ratchet wheel 131 holds it against rotation in a clockwise direction as viewed in Fig. 8, which is the direction in which the holding rod 113 must rotate to permit it to move rearwardly. Consequently, the lifting frame is held against descent, and this is true no matter what position it may occupy. When the lifting mechanism is operated to raise the lifting frame, the forward and upward movement of the lifting frame moves the holding rod 113 forward, and because of its engagement with the stationary nut 123 it rotates in a counter-clockwise direction as viewed in Fig. 8, coincidently with its forward movement, the ratchet wheel 131 rotating with it. Assuming the lifting frame to be raised by repeated strokes of the lifting lever 31, during each backward or idle stroke of said lever, the holding rod 113 will hold the lifting frame at the point to which it has been lifted, because of the inability of said rod to rotate in the opposite direction through the nut 123. When it is desired to lower the lifting frame, the operator depresses the foot lever 107, thereby operating the detent 132 to release the ratchet wheel 131, which permits the holding rod 113 to rotate in a clockwise direction, and, consequently, to move rearwardly. The rearward movement of the holding rod 113 in the cylinder 115 is resisted by the air or other fluid contained in the cylinder between its rear end and the piston 114, which in the present instance operates as a dash-pot to cushion the descent of the load. Obviously, although I have chosen in the present instance to show

a simple dash-pot arrangement for this purpose, the checking means may be of the type employing a liquid arranged to by-pass the piston as the holding rod reciprocates.

6 The operation of the lifting mechanism has already been described, but it may be remarked that the operating lever 31 may be swung back and forth to operate the lifting mechanism, regardless of the steering position 10 of said lever, since when it is swung to one side of the other for steering purposes, the link 74 accommodates itself to the changed position of said lever, and maintains its operative connection with the arm 15 70. If the operator desires an increase of power he may obtain it by shifting the link 74 to one of the lower notches 73 of said arm, and when he has lifted the load to the desired height, if he wishes to disconnect the 20 lever 31 from the lifting mechanism for greater ease in manipulation of the truck, he may do this by swinging the latch 36 to disconnect it from the horn 35. This may be accomplished automatically by depressing 25 the steering lever 31 and then lifting it slightly, whereupon the counterbalance 41 will swing said latch out of operative position. When he desires to again connect the lifting lever 31 with the lifting mechanism he simply 30 swings said lever upward to about the position shown in Fig. 2, whereupon the counterbalance ordinarily returns the latch to its operative position, so that by further backward movement of said lever the latch will 35 again engage the horn, as shown in Fig. 6. In case the counterbalance should fail to operate properly engagement of the arm 41^a with the horn will positively move the latch to its operative position. By then moving 40 the lever 31 further back, the arm 70 will be rocked rearwardly, moving the operating rod 81 down through the nut 83 preparatory to a lifting stroke of the lifting lever.

It will be seen that the same mechanical 45 principle is utilized in both the lifting and the holding mechanism, the arrangement of corresponding parts being, however, reversed. For example, in the case of the lifting mechanism, the nut 83 rotates upon the 50 operating rod 81, which does not rotate, whereas in the case of the holding mechanism the nut 123 does not rotate and the holding rod 113 rotates. In both cases, however, there is a rotatable member (the nut 83 of 55 the lifting mechanism, and the holding rod 113 of the holding mechanism) that by its rotation is caused to move endwise relatively to a non-rotatable member, (the operating rod 81 of the lifting mechanism, and the nut 60 123 of the holding means), and except when rotating is held by such non-rotatable member against endwise movement. Also, in both cases means is provided, (the ratchet wheel 84 and detent 99 of the lifting mechanism, and the ratchet wheel 131 and detent 65

132 of the holding means), for normally holding the rotatable member against rotation in one direction while permitting it to rotate in the opposite direction. So far as I am aware I am the first in the art to provide 70 lifting and holding mechanism operating in this way. The provision of the connections having the three points of contact, as described, is also an important innovation in lift trucks, and so also is the rear axle assembly. Therefore, the claims hereinafter made are intended to be construed generically except in so far as they may be directed to 75 particular features of the construction shown and described.

What I claim as my invention and desire to secure by Letters Patent, is:—

1. In a lift truck, the combination with main and lifting frames, of means for controlling the position of the lifting frame relatively to the main frame, comprising cooperating rotatable and non-rotatable members 80 movable relatively to each other by rotation of said rotatable member, one of said members being connected with one of said frames, and the other member being connected with the other frame, and means for normally holding said rotatable member against rotation in one direction, while permitting it to rotate in the opposite direction.

2. In a lift truck, the combination with main and lifting frames, of means for controlling the position of the lifting frame relatively to the main frame, comprising cooperating rotatable and non-rotatable members 90 movable relatively to each other by rotation of said rotatable member, said rotatable member being connected with said lifting frame, and said non-rotatable member being connected with the main frame and having movable engagement with said rotatable member, and means for normally holding said rotatable member against rotation in one direction, while permitting it to rotate in the opposite direction.

3. In a lift truck, the combination with main and lifting frames, of means for controlling the position of the lifting frame relatively to the main frame, comprising cooperating rotatable and non-rotatable members 100 movable relatively to each other by rotation of said rotatable member, said members having screw-threaded engagement with each other, one of said members being connected with one of said frames, and the other member being connected with the other frame, and means for normally holding said rotatable member against rotation in one direction, while permitting it to rotate in the opposite direction.

4. In a lift truck, the combination with main and lifting frames, of means for controlling the position of the lifting frame relatively to the main frame, comprising cooperating rotatable and non-rotatable members 115 120 125 130

- movable relatively to each other by rotation of said rotatable member, said members having screw-threaded engagement with each other, said rotatable member being connected with said lifting frame, and said non-rotatable member being connected with the main frame and having movable engagement with said rotatable member, and means for normally holding said rotatable member against rotation in one direction, while permitting it to rotate in the opposite direction. 5
5. In a lift truck, the combination with main and lifting frames, of means for controlling the position of the lifting frame relatively to the main frame comprising a rotatable member movable with the lifting frame when the same is raised or lowered, a non-rotatable member connected with the main frame and having screw-threaded engagement with said rotatable member, for rotating the same by relative axial movement of said members, and means for normally holding said rotatable member against rotation in one direction, while permitting it to rotate 10 in the opposite direction. 20
6. In a lift truck, the combination with main and lifting frames, of means for controlling the position of the lifting frame relatively to the main frame comprising a screw-threaded rod, a nut operating on said rod, said nut being connected with one of said frames, and said rod being connected with the other frame, and means for normally holding said rod and nut against relative rotation 25 in one direction, while permitting relative rotation thereof in the opposite direction. 30
7. In a lift truck, the combination with main and lifting frames, and a lifting lever, of means operable by said lever to lift the lifting frame, comprising cooperating rotatable and non-rotatable members movable relatively to each other by rotation of said rotatable member, one of said members being mounted in substantially fixed relation to one 40 of said frames, and the other member being connected with the other frame, and means for normally holding said rotatable member against rotation in one direction, while permitting it to rotate in the opposite direction. 45
8. In a lift truck, the combination with main and lifting frames, and a lifting lever, of means operable by said lever to lift the lifting frame, comprising an operating rod reciprocable by said lever, a member movable 50 with the lifting frame and rotatable relatively to said rod by reciprocation thereof, and means for normally preventing relative rotation of said member and rod in one direction, while permitting such rotation in the opposite direction, and means for normally holding the lifting frame against descent. 55
9. In a lift truck, the combination with main and lifting frames, and a lifting lever, of means operable by said lever to lift the 60 lifting frame, comprising an operating rod reciprocable by said lever, a nut movable with the lifting frame, and rotatable on said rod by reciprocation thereof through said nut, and means for normally preventing rotation of said nut in one direction, while permitting it to rotate in the opposite direction, and means for normally holding the lifting frame against descent. 70
10. In a lift truck, the combination with main and lifting frames, and a lifting lever, of means operable by said lever to lift the lifting frame, comprising an operating rod reciprocable by said lever, a nut movable with the lifting frame, and rotatable on said rod by reciprocation thereof through said nut, and ratchet devices carried by the lifting frame for normally preventing rotation of said nut in one direction, while permitting it to rotate in the opposite direction, and means for normally holding the lifting frame 75 against descent. 80
11. In a lift truck, the combination with main and lifting frames, and a lifting lever, of means operable by said lever to lift the lifting frame, comprising an operating rod reciprocable by said lever, a nut having a rocker bearing on and movable with the lifting frame, and rotatable on said rod by reciprocation thereof through said nut, and means for normally preventing rotation of said nut in one direction, while permitting it to rotate in the opposite direction, and means for normally holding the lifting frame 85 against descent. 90
12. In a lift truck, the combination with main and lifting frames, a lifting lever, and means operable by said lever to lift the lifting frame, of means for holding the lifting frame against descent, comprising cooperating rotatable and non-rotatable members 95 movable relatively to each other by rotation of said rotatable member, one of said members being connected with one of said frames, and the other member being connected with the other frame, and means for normally holding said rotatable member against rotation in one direction, while permitting it to rotate in the opposite direction. 100
13. In a lift truck, the combination with main and lifting frames, a lifting lever, and means operable by said lever to lift the lifting frame, of means for holding the lifting frame against descent, comprising a rotatable member movable with the lifting frame when the same is raised or lowered, a non-rotatable member connected with the main frame and having screw-threaded engagement with said rotatable member, for rotating the same by relative axial movement of said members, and means for normally holding said rotatable member against rotation in one direction, while permitting it to rotate in the opposite direction. 110
14. In a lift truck, the combination with main and lifting frames, a lifting lever, and 115

means operable by said lever to lift the lifting frame, of means for holding the lifting frame against descent, comprising a rotatable screw-threaded rod movable with the lifting frame when the same is raised or lowered, a nut connected with the main frame, said rod operating in said nut, and means for normally holding said rod against rotation in one direction while permitting it to rotate in the opposite direction.

15. In a lift truck, the combination with main and lifting frames, a lifting lever, and means operable by said lever to lift the lifting frame, of means for holding the lifting frame against descent, comprising a rotatable screw-threaded rod movable with the lifting frame when the same is raised or lowered, a nut connected with the main frame, said rod operating in said nut, and ratchet devices carried by the lifting frame for normally preventing rotation of said rod in one direction while permitting it to rotate in the opposite direction.

16. In a lift truck, the combination with main and lifting frames, a lifting lever, and means operable by said lever to lift the lifting frame, of means for holding the lifting frame against descent, comprising a frame having a rocker bearing on the lifting frame, a rotatable screw-threaded rod connected with the latter frame and movable endwise with the lifting frame when the same is raised or lowered, a nut carried by the main frame, said rod operating in said nut, and means for normally preventing said rod from rotating in one direction while permitting it to rotate in the opposite direction.

17. In a lift truck, the combination with main and lifting frames, a lifting lever, and means operable by said lever and having rocker bearing engagement with the lifting frame, for lifting the same, of means for holding the lifting frame against descent comprising a rotatable member having a rocker bearing connection with the lifting frame and movable therewith when the same is raised or lowered, a non-rotatable member connected with the main frame and having screw-threaded engagement with said rotatable member for rotating the same by relative axial movement of said members, and means for normally holding said rotatable member against rotation in one direction while permitting it to rotate in the opposite direction.

18. In a lift truck, the combination with main and lifting frames, a lifting lever, and means operable by said lever to lift the lifting frame, of means for holding the lifting frame against descent, comprising a cylinder mounted on the main frame, a piston operating therein, a rotatable piston rod for said piston connected to move with the lifting frame when the same is raised or lowered, a portion of said piston rod being screw-

threaded, a nut connected with the main frame, said piston rod operating through said nut, and means for normally holding said rod against rotation in one direction while permitting it to rotate in the opposite direction.

19. In a lift truck, the combination with main and lifting frames, a lifting lever, and means operable by said lever to lift the lifting frame, comprising an operating rod reciprocal by said lever, a member movable with the lifting frame and rotatable relatively to said rod by reciprocation thereof, and means for normally preventing relative rotation of said member and rod in one direction while permitting such rotation in the opposite direction, of means for normally holding the lifting frame against descent comprising a rotatable rod connected to move with the lifting frame when the same is raised or lowered, a non-rotatable member connected with the main frame and having screw-threaded engagement with said rod, for rotating the same by relative axial movement of said rod and non-rotatable member, and means for normally holding said rod against rotation in one direction while permitting it to rotate in the opposite direction.

20. In a lift truck, the combination with main and lifting frames, a lifting lever, and means operable by said lever to lift the lifting frame, comprising an operating rod reciprocal by said lever, a member movable with the lifting frame and rotatable relatively to said rod by reciprocation thereof, and means for normally preventing relative rotation of said member and rod in one direction while permitting such rotation in the opposite direction, of means for normally holding the lifting frame against descent comprising a piston rod connected to move with the lifting frame when the same is raised or lowered, a nut carried by the main frame and having screw-threaded engagement with said piston rod, for rotating the same by relative axial movement of said rod and nut, means for normally holding said piston rod against rotation in one direction while permitting it to rotate in the opposite direction, a cylinder connected with the main frame, and a piston carried by said piston rod and operating in said cylinder.

21. In a lift truck, the combination with main and lifting frames, a lifting lever, and means operable by said lever to lift the lifting frame, comprising an operating rod reciprocal by said lever, a member having rocker bearing engagement with the lifting frame, said member being movable with the lifting frame and rotatable relatively to said rod by reciprocation thereof, and means for normally preventing relative rotation of said member and rod in one direction while permitting such rotation in the opposite direction, of means for normally holding the lift-

- ing frame against descent comprising a rotatable piston rod having rocker bearing connection with the lifting frame and movable therewith when the same is raised or lowered, a nut carried by the main frame and having screw-threaded engagement with said piston rod, for rotating the same by relative axial movement of said rod and nut, means for normally holding said piston rod against rotation in one direction while permitting it to rotate in the opposite direction, a cylinder having a rocker bearing connection with the main frame, and a piston carried by said piston rod and operating in said cylinder. 5
22. In a lift truck, the combination of main and lifting frames, a lifting lever mounted on the main frame, and an operating connection between said lever and the lifting frame comprising a bearing member having three rocking points of contact with two bearing surfaces on the lifting frame disposed in angular relation to each other. 20
23. In a lift truck, the combination with main and lifting frames, means operable to lift said lifting frame, and a check device interposed between said main and lifting frames, comprising a bearing member having three rocking points of contact with two bearing surfaces on one of said frames, disposed in angular relation to each other. 25
24. In a lift truck, the combination with main and lifting frames, a lifting lever mounted on the main frame, a member operable by said lever to lift the lifting frame, a hook carried by said lever for operatively connecting it with said members, and means operable by the rearward movement of said lever to positively move said hook into engagement with said member. 30
25. In a lift truck, the combination with main and lifting frames, a lifting lever mounted on the main frame, lifting mechanism comprising a pivoted arm mounted on the main frame and connected with the lifting frame, and a link connected with said lever and adjustably connected with said arm for actuating said arm by said lever. 35
26. In a lift truck, the combination with main and lifting frames, of means for controlling the position of the lifting frame relatively to the main frame, comprising cooperating rotatable and non-rotatable members movable relatively to each other by rotation of said rotatable member, and means for normally holding said rotatable member against rotation in one direction, while permitting it to rotate in the opposite direction. 40
27. In a lift truck, the combination with main and lifting frames, of means for controlling the position of the lifting frame relatively to the main frame, comprising cooperating rotatable and non-rotatable members movable relatively to each other by rotation of said rotatable member, said members hav- 45
- ing screw-threaded engagement with each other, and means operable independently of the non-rotatable member for normally holding said rotatable member against rotation in one direction, while permitting it to rotate in the opposite direction. 70
28. In a lift truck, the combination with main and lifting frames, a lifting lever, and means operable by said lever to lift the lifting frame, of means for holding the lifting frame against descent, comprising cooperating rotatable and non-rotatable members movable relatively to each other by rotation of said rotatable member, and means for normally holding said rotatable member against rotation in one direction, while permitting it to rotate in the opposite direction. 75
29. In a lift truck, the combination with main and lifting frames, a lifting lever, and means operable by said lever to lift the lifting frame, of means for holding the lifting frame against descent, comprising a rotatable screw threaded rod, a non-rotatable nut movable along said rod to rotate the same when the lifting frame is raised or lowered, and means for normally holding said rod against rotation in one direction while permitting it to rotate in the opposite direction. 80
30. In a lift truck, the combination with main and lifting frames, a lifting lever, and means operable by said lever to lift the lifting frame, of means for holding the lifting frame against descent, comprising a rotatable screw threaded rod, a non-rotatable nut movable along said rod to rotate the same when the lifting frame is raised or lowered, and ratchet devices for normally preventing rotation of said rod in one direction while permitting it to rotate in the opposite direction. 85
31. In a lift truck, the combination with main and lifting frames, a lifting lever, and means operable by said lever to lift the lifting frame, of means for holding the lifting frame against descent, comprising a rotatable screw threaded rod, a non-rotatable nut movable along said rod to rotate the same when the lifting frame is raised or lowered, ratchet devices for normally preventing rotation of said rod in one direction while permitting it to rotate in the opposite direction. 90
32. In a lift truck, the combination with main and lifting frames, a lifting lever and means operable by said lever to lift the lifting frame, of means for holding the lifting frame against descent, comprising a cylinder, a piston operating therein, a rotatable piston rod for said piston adapted to be rotated by the raising or lowering of the lifting frame, and means for normally holding said piston rod against rotation under 125

- the weight of the load while permitting it to rotate when the lifting frame rises.
33. In a lift truck, the combination with main and lifting frames, a lifting lever and means operable by said lever to lift the lifting frame, of means for holding the lifting frame against descent comprising a rotatable rod, means cooperating with said rod to rotate the same with the raising or lowering of the lifting frame, and means for normally holding said rod against rotation under the weight of the load, while permitting it to rotate when the lifting frame rises.
34. In a lift truck, the combination with main and lifting frames, a lifting lever and means operable by said lever to lift the lifting frame, of means for holding the lifting frame against descent comprising a rotatable rod movable endwise with the raising or lowering of the lifting frame, means cooperating with said rod to rotate the same when it is moved endwise, and means for normally holding said rod against rotation under the weight of the load, while permitting it to rotate while the lifting frame rises.
35. In a lift truck, the combination with main and lifting frames, a lifting lever and means operable by said lever to lift the lifting frame, of means for holding the lifting frame against descent comprising a rotatable rod, a non-rotatable element movable endwise relatively to said rod with the raising or lowering of the lifting frame, and operating by such endwise movement to rotate said rod, and means for normally holding said rod against rotation in one direction while permitting it to rotate in the opposite direction.
36. In a lift truck, the combination of main and lifting frames, a lifting lever mounted on the main frame, lifting devices operable to lift the lifting frame, and connecting means between said lever and said lifting devices adjustable to effect the lifting of the lifting frame to its maximum height either by a single stroke of said lifting lever or by a plurality of short strokes thereof.
37. In a lift truck, the combination of main and lifting frames, a lifting lever mounted on the main frame, lifting devices operable to lift the lifting frame, connecting means between said lever and said lifting devices adjustable to effect the lifting of the lifting frame to its maximum height either by a single stroke of said lifting lever or by a plurality of short strokes thereof, and holding means for holding the lifting frame against descent at all stages of the lifting operation.
38. In a lift truck, the combination with main and lifting frames, a lifting lever, and means operable by said lever to lift the lifting frame, of means for holding the lifting frame against descent, comprising a rotatable screw threaded rod having a rocker bearing

on one of the frames, a nut connected to move with the other of said frames, said rod operating in said nut, and means for normally preventing said rod from rotating in one direction while permitting it to rotate in the opposite direction.
